UNITED STATES PATENT OFFICE.

FRANK L. PLATT, GEORGE N. HEIN, AND ROBERT R. IMPEY, OF SAN FRANCISCO,
CALIFORNIA.

WASHERLESS REMOVABLE-TIP HYPODERMIC SYRINGE.

Application filed August 17, 1922. Serial No. 582,376.

To all whom it may concern:

Be it known that we, FRANK L. PLATT, GEORGE N. HEIN, and ROBERT R. IMPEY, citizens of the United States, residing at the 5 city and county of San Francisco and State of California, have invented certain new and useful Improvements in Washerless Removable-Tip Hypodermic Syringes, of which the following is a specification.

10 In our previous inventions relating to hypodermic syringes, we have employed between the needle base and the end extending from the syringe barrel a packing gland, preferably of tin. This construction is expensive, and while effective, requires considerable machine work in the production of 15 the article.

This invention is designed to provide a fluid tight joint between the part projecting 20 from the barrel and the needle base, and is accomplished by affording a tapering seat between the two parts and forcing the parts into engagement with a wiping action.

With the above mentioned and other objects in view, the invention consists in the 25 novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the 30 invention.

To more clearly comprehend the invention, reference is directed to the accompanying drawings, wherein—

Fig. 1 is a view in side elevation of a 40 hypodermic syringe.

Fig. 2 is a longitudinal, central, sectional view of the tip end of a syringe, disclosing the preferred embodiment of our invention.

Fig. 3 is a section taken on line 3—3 of 45 Fig. 2.

Fig. 4 is a view in elevation, partly in section, of the removable coupling illustrated in the present embodiment of the invention.

Fig. 5 is a view in elevation of the needle 50 base.

Referring more particularly to the drawings, wherein like characters of reference designate corresponding parts—1 indicates a conventional barrel, within which is the 55 plunger 2.

In the present embodiment, a removable tip 3 is mounted in the discharge opening 4 and the discharge end of the tip is formed with a conical recess 5. Adapted for threaded connection with the tip 3 is a coupling 6, to the outer threaded end of which is connected the adapter 7 formed with a polygonal recess 8 in which is received the polygonal portion of the needle base 9 mounting a tubular needle 10. The free end 65 of the base 9 is of conical formation, as at 11, to be received in the recess 5 of tip 3.

It will be observed that the base 9 is insertable within the recess 8, and on the coupling of the parts 7 and 6, the tapering end 70 11 of the needle base is forced into the recess 5 of the tip 3 with a wiping action, providing a fluid tight joint, which is adapted to be made without the aid of a wrench and by the pressure of the fingers. 75

We claim:

1. A hypodermic syringe including a tubular barrel provided with a discharge orifice, a needle, a tubular base mounting the needle, said base formed with a conical 80 end and a polygonal periphery, a tubular part associated with the barrel and provided with a conical seat in which the conical end of said base is received, and a tubular member for receiving said needle and the base 85 and adapted for seating said conical needle base in said conical seat with a wiping action.

2. A hypodermic syringe including a tubular barrel provided at its discharge end with a tubular tip formed at its end 90 with a tapering recessed seat, a tubular needle, a tubular base mounting the same and formed with an outwardly tapering end for reception within said recessed seat, and means engaging the needle base to cause the 95 same to rotate therewith for detachably securing said needle base to said tip by a wiping contact between the surface of said tapering seat and base end.

3. A hypodermic syringe comprising— 100 a tubular needle and a tubular base mounting the same, said base being polygonal in cross section and formed with a conical end.

4. A hypodermic syringe, comprising two 105 tubular parts adapted for threaded connection, a needle and needle base removably receivable within one of said parts and held for rotation therewith on the assembling and disassembling of said two tubular parts, said 110

- base provided with a tapering end adapted for reception within a corresponding recess with cooperating walls in frictional contact to provide a fluid tight joint.
5. A hypodermic syringe including a tubular tip provided at its end with a recess, a tubular member for securing to the syringe at the end of said tip, a needle and needle base removably carried by said tubular member to rotate therewith, said needle base provided with an end adapted for reception within said tip recess with cooperating walls in direct contact to provide a fluid tight joint on the threading of said tubular member in position at the outer end of said tip.
6. A hypodermic syringe including a tubular barrel provided with a discharge orifice, a needle, a tubular base mounting the needle, said base being formed with a polygonal periphery, a tubular part associated with the barrel and provided with a conical seat in which the end of said base is received, and a tubular member for receiving said needle and said base and adapted for forcing the wall of said needle base into engagement with the wall of said conical seat with a wiping action.

In testimony whereof we have signed our names to this specification.

FRANK L. PLATT.
GEORGE N. HEIN.
ROBT. R. IMPEY.
